FORK OR SIMILAR ARTICLE OF FLATWARE

Gunter Schmidt, Solingen, Germany, assignor to Paul Wirths Metallwarenfabrik, Solingen, Germany, a special partnership

Filed Feb. 5, 1968, Ser. No. 10,432

Claims priority, application Germany Aug. 18, 1967

Term of patent 14 years

U.S. Cl. D54—12

Int. Cl. D7—03

FIG. 1 is a front elevation of a fork or similar article of flatware showing my design;

FIG. 2 is a side elevation;

FIG. 3 is a rear elevation;

FIG. 4 is a transverse section taken on line 4—4 of FIG. 1;

FIG. 5 is a transverse section taken on line 5—5 of FIG. 1;

FIG. 6 is a transverse section taken on line 6—6 of FIG. 1; and

FIG. 7 is an enlarged fragmentary view taken along the right-hand edge of FIG. 1.

The essential features of my design reside in the portions shown in full lines in the drawing.

I claim:

The ornamental design for a fork or similar article of flatware, as shown and described.
